UNITED STATES PATENT OFFICE.

HOBART B. IVES, OF NEW HAVEN, CONNECTICUT.

FASTENING FOR MEETING-RAILS OF SASHES.

SPECIFICATION forming part of Letters Patent No. 317,540, dated May 12, 1885.

Application filed January 28, 1885. (No model.)

To all whom it may concern:

Be it known that I, HOBART B. IVES, a citizen of the United States, residing at New Haven, in the county of New Haven and State of Connecticut, have invented a new and useful Improvement in Sash-Fasteners, of which the following is a specification.

My invention relates to an improvement in sash-fasteners, and has for its object to provide a means for locking the latch of the sash-fastener, so that when the latch is locked it will unlock only by the turn of the sash-lock crank.

The invention consists in a locking-notch and guide formed in the base-plate, as hereinafter more fully described, and particularly pointed out in the claim.

In the drawings, Figure 1 is a perspective view of my improved sash-fastener. Fig. 2 shows the latch mounted upon the base-plate. Fig. 3 shows a top view of the base-plate. Fig. 4 is a central vertical section. Fig. 5 shows the crank mounted upon the latch. Fig. 6 shows the under side of the crank, and Fig. 7 a side view of the latch.

In the drawings, A denotes the latch of my improved sash-fastener. It is mounted upon a base-plate, B, which is secured to the meeting-rail of the lower sash. The latch is adapted to oscillate through about one-quarter of a revolution and engage a hook, D, raised upon a base-plate, C, secured to the meeting-rail of the upper sash. It is very essential that the latch shall remain locked when engaged with the hook D, so that it will turn only by the movement of its crank E. To this end the base-plate B is formed with a raised surface, F, conforming in size and shape to the body of the latch. A portion of this raised surface is cut away on one side, so as to leave a straight inclined edge, G, forming a guide.

In the opposite side of the raised part F a notch, H, is formed, and in the center of the surface is a perforation, i.

The latch A is formed with a lateral projecting hook, k, and has two projections, m m', on its lower surface. In the center of the body of the latch is a straight longitudinal slot, n, which joins a transverse curved slot, o.

The crank E is a lever formed with a circular flat surface, p. In the center of the surface p a stud, r, is cast, and eccentric to the stud is a short projection, s.

Constructed as above described and shown, the operation of my sash-fastener is as follows: The latch A is mounted upon the base-plate B, with the projections m m' downward. The crank E is mounted upon the latch, with the projection s in the slot o and the stud r passing down through the slot n and perforation i in the base-plate, and also through a washer, t, over which it is riveted, thus securing a 55 the parts of the fastener in place. As the crank E is rotated through a quarter-turn, the projection s drives the latch around till it engages the hook k, and at the same instant the projection m' on the latch strikes the inclined edge G on the base-plate. Another quarter-turn of the crank carries the projection m' along the guiding-edge G, and simultaneously 60 moves the short projection s in the slot o in the latch, and by the joint action of these 65 parts the latch A is moved laterally across the base-plate, clamping the sashes together, and also drawing the projection m into the 70 notch H, out of which it can be moved only by turning the crank in a reverse direction. The raised part F being as large as the body 75 of the latch, the notch H is at such a distance from the center of the stud r that there is little vibration of the latch, even when the projection m fits loosely into the notch H, which it must necessarily do, as the parts of the lock are put together just as they come from the foundry without fitting or finishing. 80

I claim as new and desire to secure by Letters Patent—

The combination, with the base plate B, having central perforation, i, notch H, and guiding-edge G, of the latch A, and crank E, all 85 constructed and arranged in the manner and for the purpose substantially as described.

HOBART B. IVES.
